(57) **CLAIM**

The ornamental design for a set of vehicle floor mats, as shown and described.

DESCRIPTION

FIG. 1 is a top rear right perspective view of a driver's side mat according to our design;

FIG. 2 is a plan view of the driver's side mat;

FIG. 3 is a rear view of the driver's side mat;

FIG. 4 is a right side view of the driver's side mat;

FIG. 5 is a left side of the driver's side mat;

FIG. 6 is a front view of the driver's side mat;

FIG. 7 is a top rear right perspective view of a passenger's side mat according to our design;

FIG. 8 is a plan view of the passenger side mat;

FIG. 9 is rear view of the passenger side mat;

FIG. 10 is a right side view of the passenger side mat;

FIG. 11 is a left side view of the passenger side mat;

FIG. 12 is a front view of the passenger side mat;

FIG. 13 top rear right perspective view of a second row mat incorporating our design;

FIG. 14 is a plan view of the second row mat;

FIG. 15 rear view of the second row mat;

FIG. 16 is a left side view of the second row mat;

FIG. 17 is a right side view of the second row mat; and,

FIG. 18 is a front view of the second row mat.

The bottom surfaces of the mats incorporating our design are unadorned and forms no portion of the claimed design.
